UNITED STATES PATENT OFFICE.

EDWIN J. BLOOD, OF CHICAGO, ILLINOIS.

TUG-ADJUSTER FOR HARNESS.

SPECIFICATION forming part of Letters Patent No. 237,086, dated February 1, 1881.

Application filed May 15, 1880. (No model.)

To all whom it may concern:

Be it known that I, EDWIN J. BLOOD, of the city of Chicago, in the county of Cook and State of Illinois, have invented a certain new and useful Improvement in Tug-Adjusters; and I do hereby declare that the following is a full, clear, and exact description of the same, reference being had to the accompanying drawings, in which—

Figure 1 represents a plan view of a modification of my invention. Fig. 2 represents a longitudinal vertical section of the same.

The same letters denote the same parts in all the drawings.

My invention relates to the tugs or straps by which the body-harness of draft-animals is connected with the vehicle to be drawn; and the object of it is to provide a means by which the length of the connection may be readily varied while maintaining security of attachment to the vehicle. This object I attain by extending the base of the tug-hook (or connection of the tug with the hame) into a bar having attachments adapted to interlock with corresponding attachments on the tug-strap.

In the drawings, A denotes a bar, having at one end the tug-hook *a*, by which it may be attached to the hame. Its upper surface, B, is depressed so as to form a groove or channel, in which the tug-strap may have a longitudinal but no lateral motion. The middle part of this surface may be cut out, as shown in the drawings, so as to leave merely a track at each side for the strap to run on. The sides of this channel or groove are connected at intervals by cross-bars or bridges C. The tug-strap D is made of suitable width to slide easily, without lateral motion, in the channel B, and has at the end nearest the hame a hook or catch, E, of suitable size and shape to take firm hold of either of the bridges C, but readily detachable from them by being pushed backward. Under this hook or catch is attached to the

tug a spring, F, whose elasticity is sufficient to press the catch firmly against the bridge, so that the strap can have no motion in the channel, except by applying a compressive force directly to the spring. The tug therefore cannot be loosened by any motion of the animals or of the vehicle, while by firmly grasping the catch and spring and drawing the tug backward it is at once detached, and may then be hooked onto another bridge backward or forward of that from which it has been removed. Then, by releasing the spring and catch from the grasp, the tug is held firmly in its new place. It is obvious that this device may be applied to any apparatus in which a flexible connection of variable length between two points is desired.

What I claim as my invention, and desire to secure by Letters Patent, is—

1. The bar A, having the hook *a* and channel B, in combination with the strap D, capable of longitudinal motion in the channel, the spring F, affixed to the under side of the strap, and a stop-catch, one member of which is secured to the upper side of the strap, and the other to the bar above the strap, whereby the two parts of the catch are caused to interlock by a pull on the strap under the outward pressure of the spring, substantially as described.

2. The bar A, having the hook *a*, channel B, and bridges C, in combination with the strap D, adapted to have a longitudinal motion in the channel, and having the catch E, adapted to lock on either of the bridges, and the spring F, adapted to hold it locked, all constructed, arranged, and operating substantially as described.

EDWIN J. BLOOD.
